UNITED STATES PATENT OFFICE.

CHARLES T. HOWSON, OF SILVER CREEK, NEW YORK.

ROLLER MILL.

Continuation of application Serial No. 247,560, filed July 31, 1918. This application filed July 12, 1920.
Serial No. 395,461.

To all whom it may concern:

Be it known that I, CHARLES T. HOWSON, a citizen of the United States, residing at Silver Creek, in the county of Chautauqua and State of New York, have invented certain new and useful Improvements in Roller Mills, of which the following is a specification.

My invention relates to improvements in 10 roller mills, and more particularly to that type generally referred to as self-contained roller mills in which the various parts are confined within a single enclosure and into which the grain is introduced and operated 15 upon in its flow through the mill and discharged in the form of flour, with separate provision made for discharging clean finished bran and for disposing of the offal; this invention being a continuation of my 20 co-pending application, Serial No. 247,560, now Patent #1,522,456 Jan. 6, 1925.

One of the objects of my invention is to provide a mill of this kind with improved feeding or distributing mechanism in association with a pair of reduction rolls so that the stock passing through said feeding or distributing mechanism will be distributed evenly throughout the lengths of said rolls.

Another object of my invention is to provide means within a mill of this kind whereby, in the course or process of making flour, the stock or middlings are separated to direct the finer and coarser particles thereof into two different channels, the finer 35 particles being delivered to a pair of reduction rolls and the coarser to a middlings grinder, both so associated that the stock or material passing through them are brought together in considerably finer form and con- 40 veyed together to, or separately if desired, a bolting reel or reels, thus assuring greater production from a given quantity of stock.

A further object of my invention is to provide means for separating the middlings 45 according to fineness, reducing or grinding the separated parts separately, and directing the separated parts into a channel common to both, from which it may be led to bolting means for bolting out the flour 50 therefrom.

A further object is to provide a machine of this kind with an improved feeder or distributor whereby the material passing therethrough may be retarded in its escape therefrom, whereby such material may be 55 delivered therefrom in varying quantities, and whereby the distribution may be extended over varying lengths of the feeder or distributor, if desired.

A further object is to provide an im- 60 proved conveyer arranged partly within an enclosure and provided with means for discharging the material conveyed by said conveyer laterally from said enclosure.

A further object of my invention is to 65 provide means within the roll section of a roller mill of this kind for grading middlings and delivering the same to two different means of reduction and sending the products of the two different reducing 70 means to suitable bolting means for bolting the flour therefrom.

A further object of my invention is to grade middlings within the reel section and to deliver one grade thereof to a suitable 75 grinder or reducing device and return the same to the reel section for bolting out the flour therefrom.

A still further object of my invention is to provide in a machine of this type having 80 the usual break and reduction rolls and bolting reels, a reduction or grinding means separate and distinct from said rolls, whereby the capacity for reducing the stock in its course through the machine is increased, 85 which capacity in present day machines is insufficient to employ the full capacity of the reels employed for bolting out the flour from the stock.

With these and other objects in view to 90 be hereinafter described, my invention consists in the novel features of construction, and in the arrangement and combination of mechanisms and parts to be hereinafter described and more particularly pointed out in 95 the subjoined claims.

In the drawings:

Fig. 1 is a side elevation of a machine representative of one embodiment of my invention, parts of the machine being broken 100

away and the side walls removed therefrom to better illustrate operating portions of the mill.

Fig. 2 is an enlarged transverse section taken on line 2—2, Fig. 1.

Fig. 3 is an enlarged transverse section taken on line 3—3, Fig. 2, looking toward the left.

Fig. 4 is an enlarged cross section taken on line 4—4, Fig. 5.

Fig. 5 is a longitudinal section through my improved feeder or distributor.

Fig. 6 is a transverse section taken through the lower portion of the machine on line 6—6, Fig. 1.

Fig. 7 is a transverse section taken on line 7—7, Fig. 1.

Fig. 8 is a diagrammatic view of several parts of the mill showing the flow of material through the mill.

The preferred embodiment of my invention is shown by means of the several figures above referred to, in which the reference numeral 1 designates the complete unit or mill divided into three parts or sections 2, 3, 4. Said sections are separated by transverse frame members or walls 5, 6, with the outer ends of the compartments 2 and 4 closed by frame members or walls 7, 8.

The first part of section 2 may be termed the roll section, although it contains other parts directly associated with the rolls, as will be hereinafter described. The second or immediate part or section 3 is employed mainly to receive a portion of the driving mechanism, an elevator by means of which stock may be elevated from a low point of the machine to a high point, and conveyor tubes with screw-conveyers therein for purposes to be hereinafter explained. The third part or section 4 may be termed the reel section, due to the fact that in this section bolting reels are employed, although there are other parts of the machine in this section directly associated with said bolting reels, such as hoppers, conveyers, etc. The various elements confined within said parts or sections will be hereinafter fully described with reference to their relative arrangement, construction, and functions.

The frame member or wall 7 may be termed the head-end wall, while the frame member or wall 8 may be termed the tail-end wall, both of these walls forming part of the housing. These end walls and the intermediate walls 5, 6 are preferably castings formed to the shape of the mill transversely, and the various rotatable parts of the mill are journaled in these walls or in suitable bearings applied to said walls, said walls serving also to support other parts of the mill. Said walls serve as transverse frame members of the mill and are connected at the bottom by longitudinally-dis-

posed angle irons 9 serving as sills to provide proper bearing faces for contact with the floor, or other foundation on which the mill is set. Longitudinally-disposed angle irons 10 connect the upper ends of these frame members together.

Connecting the head-end frame member 7 with the adjacent intermediate frame member 5, at points between their upper and lower ends, are channel beams 11. These beams are secured to opposite side edges of the frame members and extend a distance forward or in advance of the head-end frame member 7, as clearly shown in Fig. 1. A transverse bearing member 12 is riveted or otherwise fastened at opposite ends to the outer ends of said channel beams, and midway between the ends thereof a shaft bearing 13 is secured in which the main or driving shaft 14 is journaled, said shaft extending inwardly through the roll section and being suitably journaled in the head-end frame member 7 and the intermediate member 5.

The frame work of the machine is closed at the top, bottom and sides to form a housing or closure for the machine, and for this purpose top walls 15 are provided which receive support from the opposite longitudinal channel irons 10 at the upper ends of the transverse frame members, said top walls being secured to said channel irons in any suitable manner for closing the upper ends of the sections 2 and 4. Side walls 16 are provided which close the sides of the machine and may be secured in any suitable manner to the side edges of said transverse frame members. The bottom of the machine is closed by a bottom wall or machine floor 17 which rests upon the inner faces of the horizontal webs of said angle irons or sills 9.

To the main or driving shaft 14, the main pulley 18 is secured, said pulley being positioned outside of the transverse bearing member 12.

A feed spout 19 is arranged in the top of the housing, through which the grain is fed into the machine, and a suitable cut-off or valve 20 provided within said feed spout to regulate the flow of the grain into the machine, or to entirely shut off the flow. This spout, or "feeding device" as it may be termed, projects into the roll section 2 of the machine between the transverse frame members 7 and 5, and delivers the grain onto a shoe or vibrating shaker 21 having a distributing device 22 at one end thereof. Said shoe and the distributing device may be constructed and operated in any approved manner, its purpose being to receive the grain from the feeding device, distribute the same evenly and deliver the same properly distributed to a pair of break rolls 23, 24, which break rolls, due to the

fact that other break rolls are employed, I designate the "first pair of break rolls". These break rolls are situated underneath the discharge opening 25 of said distributing device 22, and said distributing device is substantially of the same length as the break rolls 23, 24 with which it is directly associated, and by reason of said distributing device delivering the grain in a thin stream or flow the full length thereof, said rolls will be effective from end to end.

Arranged beneath said break rolls is a scalper 26 between which and said rolls a hopper 27 is situated, said hopper extending from the head-end frame member 7 to the intermediate frame member 5 and said scalper being of corresponding length. The scalper may be of any approved construction capable of separating the stock fed thereto so that part of it may be delivered to a bolting reel, to be hereinafter described, for bolting the flour therefrom, and part of it to a second pair of rolls 28, 29, situated in the roll section 2 beneath said scalper. The particular scalper shown comprises a rotary brush 30 and a suitable screen 31 of semi-cylindrical formation in cross section, said screen being secured to a screen-frame 32 suitably fastened to the two transverse frame members 7 and 5, or otherwise maintained in position within said roll section. Said screen frame 32 is preferably inclined so that the screen will tail freely at a low point, as at 33, and it may be pivotally and adjustably supported in any suitable manner, whereby the screen 31 may be adjusted toward or from the rotary brush 30 to regulate the amount of stock, such as flour and middlings, to be removed from the bran, and to more effectively clean the bran.

Beneath the semi-cylindrical screen 31, a hopper 34 is arranged, which also extends the full length of the roll section 2 and which is closed at its lower end and has a semi-cylindrical portion 35 at said lower end in which a screw conveyer 36 is arranged, for a purpose to appear herein-after.

The flour and middlings passing through the screen 31 enter the hopper 34 and are conveyed by the conveyer 36 into the reel section 4 of the frame, as will be herein-after described, while the bran with flour adhering thereto is carried over the low side of the screen frame and delivered into a hopper 37 situated beneath the hopper 34. The low end of said screen frame overhangs the corresponding side of said hopper 34 so that assurance is had that none of the bran will be delivered into the hopper 34. The hopper 37 has an open lower end delivering to the second pair of break rolls 28, 29 through which the bran is passed, and as this bran has middlings and

flour adhering thereto, it is further broken up in passing through the second pair of break rolls and is then delivered into a hopper 38 situated beneath said second pair of break rolls, said hopper delivering the same to a scalper 39 of any approved construction capable of separating the stock fed thereto so that part of it, flour and middlings, may be delivered to a bolting reel, to be hereinafter described, for bolting the flour therefrom, and part of it into a chute 40 by means of which it is delivered out of the machine to be bagged or otherwise disposed of, the material passing through the chute being bran freed of all particles capable of further use in the process of producing flour.

I have shown the scalper 39 to be of the same construction as the scalper 26 hereinbefore described, and through the screen of said scalper 39 the finer particles delivered thereto are passed and enter a hopper 41. This hopper, like the hopper 34, is closed at its lower end and has a semi-cylindrical portion 42 at said lower end in which a screw conveyer 43 is arranged.

The material having been worked through the screen of the scalper 26 and delivered to the conveyer 36, as hereinbefore described, is carried by said conveyer through a conveyer tube 44 extending from the intermediate frame member 5 to a centrifugal bolting reel 45 in the reel section 4 of the machine between the intermediate frame member 6 and the tail end frame member 8, which reel I term the "first break reel". The flour is bolted out through the silk or wire of said bolting reel and is delivered against the inclined wall 46 of a hopper 47 occupying with its upper or wide portion substantially the entire width of the machine. From the hopper 47 the flour is delivered into a second hopper 48 situated beneath one-half of the hopper 47 and therefore occupying substantially one-half the width of the machine. Said second hopper is closed at its lower end and may be substantially semi-cylindrical, as at 49, and in this semi-cylindrical portion a screw conveyer 50 is arranged which serves to convey the flour rearwardly toward the tail end of the machine, or otherwise, for delivery therefrom through a suitable outlet, which may be led to any suitable point or have connection with any suitable point for storing or packing the flour.

The middlings from the material within the first break reel 45, tail over the end of said reel and are delivered into a hopper 51 at the rear end of the machine, which hopper leads to the rear end of a conveyer tube 52 in which a screw conveyer 53 is arranged. This conveyer conveys the material to the bottom of an elevator 54 arranged in the intermediate section 3. This

elevator may be of any suitable construction, and by means of it the middlings are carried up into a conveyer tube 55, said conveyer tube being also situated in the intermediate part or section 3 of the machine and feeding into and being alined with a feeder or distributer 56 situated in the roll part or section of the machine and extending from the head end frame member 5 to the adjacent intermediate frame member 7. In preferred form the conveyer tube 55 is made to enter the end of the feeder tube or enclosure 57, as at 58. Arranged within said conveyer tube and said feeder tube is a screw conveyer 59 by means of which the middlings delivered into the conveyer tube 55 is directed forwardly into the feeder tube 57, said conveyer being suitably journaled in the head end frame member 7 and in the intermediate frame member 6. At the front end of said conveyer a flanged hub 60 is provided, to the flange of which sweeps or rods 61 are secured, said rods extending rearwardly from the flange of said hub and having their rear ends fastened to the spiral blade or portion of said conveyer, as at 62.

The feeder tube is provided at one side with a discharge slot or elongated outlet 63 which preferably extends the full length of the tube, and at one end of said tube a flanged collar 64 is arranged which has an upward extension 65 provided with a handle 66. In said flange, and more particularly in the upward extension thereof, a segmental slot 67 is formed through which is passed a stud screw 68 fastened into the intermediate frame member 5 and serving as a stop to limit the range of rotary movement of said feeder tube, due to the stop being engaged by the ends of said segmental slot when the tube reaches opposite extremes of its range of movement.

The flange 64 lies in contact with the intermediate frame member 5 and provides a suitable end bearing for said feeder tube. At the same time, said feeder tube receives bearing from the end of the conveyer tube 55 which is secured into said intermediate frame member 5 and projects through the same so as to enter the flanged end of said feeder tube. By rotating the feeder tube, the lower edge of the slot or outlet 63 therein may be brought to a higher or lower plane. In other words, said lower edge may be brought closer to the lowest point of the tube or farther from such point and the middlings conveyed into said tube will necessarily be delivered along the full length of the tube before it can be discharged through the opening thereof, the sweeps or rods 61 serving to carry or sweep the middlings upwardly so that they are discharged in even flow or stream the entire length of the slot or outlet 63. I preferably

provide said tube at the upper and lower edges of said slot or outlet with outstanding flanges 69, 70, respectively, which enable the tube to be reversed on machines where the locations of the sections 2, 3 and 70 4 are reversed.

The outstanding flange 70 at the lower edge of the slot or outlet 63 serves to prevent the middlings discharged following the curvature of the tube and particularly 75 prevents the finer particles of the middlings which may become freed from the coarser parts from adhering to the exterior surface of the feeder tube 57, and the flange at the upper edge of said slot or outlet, in addition 80 to making it possible to reverse the tube as above stated, acts as a baffle in the event of any of the material being thrown upwardly from within the tube, said material coming in contact with the upper flange and 85 falling directly onto the lower flange or over the edge of the latter.

Said feeder or distributer 56 delivers the middlings in an even stream onto the rear end of the shoe or vibrating shaker 21, and 90 this shoe or shaker has a laterally inclined receiving table 71 beneath which an oppositely-inclined screen table is arranged, the screen 72 of said table closing the upper end of a short hopper 73. At the lower end 95 of said screen 72 a solid or imperforated table portion 74 is provided, which serves as an extension of said screen 72. The middlings delivered onto the screen table are therefore graded at the rear end of the 100 shoe or shaker 21, the finer particles passing through the screen 72 and the coarser particles being delivered over the solid or imperforate extension 74 for delivery into a middlings grinder 75 of any approved 105 construction, which, in trade, is known as a device having a casing and a grinding rotor or rotatable grinding element within said casing, and having said rotor or grinding 110 element acting to grind middlings to more effectively separate the flour-yielding matter from the coarser matter, and therefore, 115 where in the claims reference is made to a middlings grinder it is not intended to mean a pair of rolls such as the break and reduction rolls described herein, or such rolls as usually referred to as break and reduction rolls, or co-acting rolls serving the purposes of such rolls. Said middlings 120 grinder is separate and distinct from all rolls of the machine and is suitably supported beneath the shoe or vibrating shaker 21. A flexible tube 76 is formed or secured on the screen extension 74 and enters the feeding opening of said grinder. 125 The outlet of said grinder has a discharge tube 77 connected thereto.

Beneath the short hopper 73 a pair of reduction rolls 78, 79 is arranged, which, for convenience, I will refer to as the "first" 130

reduction rolls", and between which the finer portion of the middlings graded in the grading device of the shoe or shaker are passed to be further reduced. The middlings reduced by these first reduction rolls are delivered into a hopper 80 situated beneath said rolls, and the coarser portion of the middlings ground by and passed through the grinder 75 is delivered from 10 the discharge tube 77 into said hopper 80 so that the middlings thus graded are brought en masse within said hopper. The lower end of said hopper is closed and formed semi-cylindrical, as at 81, and in 15 this closed lower end a screw conveyer 82 is arranged. This conveyer is continued through a conveyer tube 83 spanning the space between the intermediate members 5 and 6, said tube opening into a bolting reel 20 84. The shaft of said conveyer 82 is extended rearwardly and continued through said bolting reel, as at 85. Said bolting reel I term the "first reduction reel" and it is covered throughout a portion of its length 25 with fine bolting silk or wire 86, and has a cut-off or box-like structure 87 built around its rear end, which rear end is covered with bolting silk or wire 88 of coarser mesh than the portion 86 of said reel. The reduced 30 middlings and flour conveyed to this reel are separated therein owing to the flour passing or being worked through the fine mesh silk or wire 86, while the coarser material or middlings, which cannot pass 35 through said fine mesh silk or wire, are directed to the rear end of said reel and passed or worked through the coarser mesh silk or wire 88.

The flour or finished product passed 40 through the fine mesh portion of said first reduction reel 84 enters the hopper 47 and strikes the inclined wall 89 of the hopper 47, said inclined wall being situated underneath said bolting reel. The flour or 45 finished product is delivered from the hopper 47 into a hopper 90 which occupies a space beneath one-half the hopper 47; and it may here be stated that the outlet 50 of the hopper 47 is divided by a vertically-disposed wall 91 rising from the meeting walls at the upper ends of the hoppers 48 and 90 to form two passages 92, 93, thus the flour or finished product from the first 55 break reel 45 is directed through the passage 92 into the hopper 48, as hereinbefore stated, while the flour or finished product from the first reduction reel 84 is delivered through the passage 93 into the hopper 90. The lower end of the hopper 90 is closed and 60 formed semi-cylindrical, as at 94, and in this closed end a screw conveyer 95 is located. This conveyer 95 carries the flour or finished product to a suitable outlet in the machine from which it may be led to 65 any suitable point or have connection with any suitable point for storing or packing the flour. This flour may be stored or packed separately from the flour or finished product delivered from the hopper 48, hereinbefore referred to, or the flour or 70 finished product from both the hoppers 48 and 90 may be led into a single storage hopper or receiving receptacle or package. It will be observed therefore that the different runs of flour may be stored separately 75 or mixed together, as desired.

The material within the first reduction reel 84 not passed through the finer mesh silk or wire 86 will be worked within the portion of the reel covered with the coarser 80 silk or wire 87 and the material passing through said coarser mesh silk or wire enters the cut-off or box-like structure 87, which has a parti-cylindrical confining wall 96 provided with a discharge slot or 85 opening 97 connecting said cut-off with a conveyer tube 98 having a screw conveyer 99 therein. Said discharge slot or opening is arranged at a level somewhat above the lowest point of said parti-cylindrical wall 96, and for this reason the bolting reel is provided with sweep arms or bars 100 which serve to carry or sweep the material passing or worked through the coarse silk or wire of said bolting reel into said slot or opening 95 97 for delivery to said conveyer tube 98. Said conveyer tube 98 extends forwardly 100 through the intermediate frame members 6 and 5, for a purpose to be presently described.

The tailings from the first reduction reel 84 are discharged from the machine by any suitable means.

Located within the roll section and extending from the frame member 7 to the 105 intermediate frame member 5 is a second feeder or distributer 101 constructed and operating in the same manner as the feeder or distributer 56, hereinbefore described, the rear end of the feeder tube of said feeder 110 being supported by the front end of the conveyer tube 98, as and in the manner shown in Fig. 5 in which the feeder tube 57 is supported by the front end of the conveyer tube 55. A detailed description of this 115 second distributer or feeder 101 is not therefore deemed necessary, except to state that the conveyer 99 within the conveyer tube 98 is continued forwardly through the tube of the feeder 101 and that the rod or sweeps of this feeder have their rear ends fastened to the spiral blade of said conveyer at different points in the length thereof, substantially as explained with reference to the feeder 56; also that the elongated outlet is at the side opposite that of the outlet in the feeder tube 57, see Fig. 2. The spaced longitudinally-arranged rods 61 of each of the feeders 56 and 101 form what may be 120 termed a "squirrel cage" feeder.

The middlings delivered from the cut-off of the first reduction reel are conveyed by the conveyer 99 into the feeder or distributor 101, and from the latter are discharged in an even flow or stream into a hopper 102 situated directly over and discharged between a "second pair of reduction rolls" 103, 104, said middlings being reduced by said rolls and delivered into a hopper 105 situated beneath said rolls, said hopper having its lower end closed and formed semi-cylindrical, as at 106, and in this lower end a screw conveyer 107 is arranged. This conveyer passes through a conveyer tube 108 extending rearwardly from the inner end of the hopper 105 and connects axially with the bolting reel 109, which reel may be termed the "second reduction reel." The material from the hopper 105 is thus conveyed by the conveyer 107 into said second reduction reel.

Said second reduction reel is arranged within the hopper 90 and flour bolted through the silk or wire covering of this reel and delivered to the bottom of said hopper, from which it is conveyed by the conveyer 95 to a suitable discharge opening, as hereinbefore explained. Unsifted material or offal tails over the rear end of said reel and is suitably discharged from the machine for storing or packing or for disposal in any other manner.

Returning to the material having passed between the second pair of break rolls 28, 29, hereinbefore referred to, and having been delivered to the conveyer 43, said material is delivered rearwardly through a conveyer tube 110 connected axially with a bolting reel 111, which may be termed a "second break reel." Said second break reel is situated within the hopper 48 and is covered throughout a portion of its length with fine mesh silk or wire through which the flour from the material entering the reel passes or is worked the same as provided for in the first reduction reel 84, said fine mesh silk or wire covering being situated directly within the hopper 48 so that the flour passing therethrough falls to the bottom of the hopper 48 and is conveyed by the conveyer 50 to the flour outlet of the machine, hereinbefore first referred to, for sacking or storing the same.

At the rear end, this second break reel is surrounded by a cut-off or box-like structure 112, which has a parti-cylindrical confining wall 113 and opens at 114 into the conveyer tube 52 having the conveyer 53 located therein. The rear or cut-off end of the bolting reel is constructed the same as the rear or cut-off of the first reduction reel 84 and the coarser material or middlings passing through said cut-off is conveyed forwardly by said conveyer 53 with the middlings delivered to said con-

veyer through the hopper 51 from the first break reel 45, said conveyer leading both materials to the elevator 54, which elevates the same to the conveyer tube 55. The conveyer 59 in said conveyer tube 55 conveys the materials, now thoroughly mixed, through the feeder or distributor 56 to what I have termed the middlings grader, forming part of the shoe or shaker 21, part of said material being passed through the grinder 75 and part through the first pair of reduction rolls 78, 79, as hereinbefore explained, and being again brought together within the hopper 80, from which it is conveyed rearwardly by the conveyer 82 to the first reduction reel 84, the material having been reduced in passing through the first reduction rolls and the grinder. The flour from the reduced material within said first reduction reel passes or is worked through the fine mesh silk or wire of said reel while the coarser material is carried on within the reel and passed or worked through the coarse silk or wire of the reel within the cut-off 87 from which point it is conveyed by the conveyer 99 to the second feeder or distributor 101 and from the latter to the second pair of reduction rolls 103, 104, where it is again reduced in passing between said rolls and delivered into the hopper 105 and by the conveyer 107 within said hopper is carried to the second reduction reel 109, the flour passing through the silk or wire of said reel being delivered into the hopper 90 from which it is conveyed to a suitable outlet, hereinbefore referred to, for sacking or storage. The offal from the material within the second reduction reel is tailed over the rear end of said reel and is delivered outside of the machine, as hereinbefore explained, to be sacked or otherwise disposed of.

The break rolls may be corrugated in the usual manner while the reduction rolls are smooth surfaced. For the purpose of rotating one of each pair of said break and reduction rolls I employ a belt 115 driven from the main or drive shaft 14, said belt passing around pulleys secured to the front-end shaft-parts of said rolls. It is, however, to be understood that these rolls may be driven in any other suitable manner.

The rear-end shaft part of the other roll of each of said pair of break and reduction rolls has a pulley secured thereto around all of which a belt 116 travels, said belt being situated in the intermediate section 3 of the machine. From the rear-end shaft-part of one of said second break rolls the lower scalper 39 is driven by means of a crossed belt 117 and the upper scalper 26 is driven from the rear-end shaft-part of one of said first break rolls by a crossed belt 118. Any suitable means are employed within the intermediate section to drive

one of the rear-end-driven rolls from the driving shaft 14, which shaft extends rearwardly into said intermediate section.

The belt 115 driven by the main driving shaft 14 at the front end of the machine also passes around a pulley secured to the shaft of the conveyer 36 which last-mentioned shaft extends through the first break reel and projects out of the rear end of the machine, and from this rear-end point the remaining conveyers (excepting the conveyer 59 leading from the upper end of the elevator) and all the bolting reels of the machine are driven in any suitable manner.

15. The elevator is operated from one of the rear-end shaft-parts of one of the first break or first reduction rolls, as may be desired, by means of a crossed belt 119, and as the upper shaft of said elevator extends both 20 forwardly and rearwardly and projects with its front end through the front end of the machine, I drive the conveyer 59 from said front end by means of a sprocket and chain drive 120.

25. The middlings grinder 75 has its shaft 121 projecting from its casing and on this shaft is a pulley 122 around which and a pulley 123 on the main shaft 14, a belt 124 passes. Said belt is therefore situated within 30 the roll section 2 of the machine and serves to operate said grinder directly from the main shaft.

The bolting reels are rotatable independently of the reel or beater shafts, or as 35 they may be termed "the continuations of the conveyer shafts."

The manner of rotating the various parts of my improved machine I do not lay any claim to in this application, and the operation necessary to a full and clear understanding of the parts essential to this invention 40 will be made plain from the further description thereof.

The operation of the machine is as follows:

45. The clean wheat or other grain fed into the machine is delivered from the feed spout 19 onto the vibrating shoe or shaker, which may be operated in any suitable manner and from this shoe or shaker it is directed between the first pair of break rolls 23, 24, the wheat being suitably ground or crushed by said rolls and delivered therefrom into the rotary scalper 26. Part of the material 50 from this scalper is delivered by the conveyer 36 into the first break reel 45, while the coarser material or overtails, which does not pass through the sieve or screen of the scalper, is delivered into the hopper 57 to the second pair of break rolls, 28, 29. The first break reel acts to bolt out all the flour from the material delivered thereto, which flour is directed through the hoppers 47 and 48 to the conveyer 50 to be conveyed 55 out of the machine for storage or packing,

as may be desired. The overtails or middlings from this reel are carried through the rear end thereof and directed into the hopper 51 shown in dotted lines in Fig. 6 and built between the rear end wall 8 and a wooden transverse wall 125 spaced therefrom, and from said hopper to the conveyer 53 to be carried forward to the elevator 54 and be delivered by said elevator to the conveyer 59. Said conveyer 59 conveys these overtails or middlings to the feeder or distributor 56 which delivers it to the rear end of the shoe or shaker 21 serving as a middlings grader, the finer material being directed through the screen 72 of said middlings grader to the first pair of reduction rolls 78, 79, and the coarser material being directed to the middlings grinder 75. The materials reduced and ground respectively by said reduction rolls and grinder being brought en-masse into the hopper 80 from which it is conveyed by the conveyer 82 to the first reduction reel 84. The fine material delivered into this first reduction reel is bolted out through the fine bolting silk or wire 86 and delivered as flour into the hopper 47 and from said hopper 47 into the hopper 90 to be conveyed out of the machine by the conveyer 95 as a completed product.

The coarser material passing through said first reduction reel 84 is passed or worked through the coarser mesh silk or wire 88 forming part of the cut-off 87 and conveyed forwardly by the conveyer 99 into the roll section where it is delivered to the hopper 102 by the feeder 101, and from the hopper to the second pair of reduction rolls 103, 104. The overtails or offal from the material passing through said first reduction reel is delivered out of the machine for sacking or otherwise.

The middlings from said first reduction reel having been delivered to said second pair of reduction rolls 103, 104 are further reduced thereby and delivered into the hopper 105, from which it is conveyed rearwardly by the conveyer 107 to the second reduction reel 109 where the flour is sifted out and delivered into the hopper 90 to be discharged from the machine by the conveyer 95 as a finished product, for storing or sacking. The tailings or offal not sifted out by this reel is carried out of the rear end of said second reduction reel and delivered out of the machine in any suitable manner. This portion of the operation therefore disposes of the middlings passed through the first break reel and the middlings passed through the first reduction reel and re-conveyed through the roll section of the machine. Such operation also disposes of the first run of flour passed through said first break reel and the second and third runs of flour passed respectively through the first and second re-

duction reels, at the same time disposing of all offal passed through said reduction reels.

The coarser first run material delivered to and broken up or crushed between the 5 second pair of break rolls 28, 29, is passed through the hopper 38 and directed into the second scalper 39, the finer particles being worked through the sieve or screen of said scalper and directed into the hopper 41, while the coarse stuff is carried from the low end of said scalper into the chute 40, and by the latter delivered out of the machine for sacking, this being clean broad bran which may be sacked and sold.

15 The finer material delivered to the conveyer 43 is conveyed rearwardly to the second break reel 108, which is provided with a fine mesh silk or wire portion and a coarser mesh silk or wire portion within 20 a cut-off, as hereinbefore stated. The flour is bolted out of this reel through the finer mesh silk or wire portion and delivered to the bottom of the hopper 48 where it is conveyed out of the machine by conveyer 50 for 25 sacking or storage as a finished product. The coarser material or middlings is worked or passed through the coarser mesh silk or wire in the cut-off 112 and delivered to the conveyor 53, by which it is conveyed to 30 the lower end of the elevator 54 and delivered at the upper end of said elevator to the conveyer 59, said conveyer delivering it to the feeder or distributer 56, from which it drops onto the middlings-grader portion 35 of the shoe or shaker 21 and is directed through the first reduction rolls 78, 79, and also through the middlings grinder 75. The two separated portions of this material are again brought together within the hopper 40 and conveyed by the conveyer 82 into the 40 first reduction reel 84. The flour is sifted out of this material through the fine mesh silk or wire 86 and directed into the hopper 47 and from the latter into the hopper 90 45 to be conveyed out of the machine as a finished product by the conveyer 95. The coarser material in this first reduction reel is passed or worked through the coarser mesh silk or wire 88 of the cut-off 87 of 50 said reel and carried to the conveyer 99 from which it is directed forwardly into the roll section and delivered from the second feeder or distributer 101 to the second pair of reduction rolls 103, 104, to be further reduced thereby. From these rolls the material is delivered into the hopper 105 and conveyed by the conveyer 107 to the second reduction reel 109, from which the flour is sifted out and enters the hopper 90 to be 55 conveyed from the machine by the conveyer 95 for sacking or storage, the offal being tailed out through the rear end of said reel and delivered out of the machine in any suitable manner. The offal remaining after 60 sifting out the material through the cut-off 65

of the first reduction reel is also tailed out from the rear end of said reel and delivered out of the machine in any suitable manner.

From the foregoing, it is apparent that stock fed into the machine is carried through a portion of the machine a second time, and that, therefore, a larger yield of flour is obtainable from a given quantity of stock than would be otherwise possible. At the same time, provision is made so that only high quality flour is produced through the operation of the parts, since tailings or offal are conveyed out of the machine at different times during the passage of the stock through the machine.

By combining a conveyer with a feeder or distributer and utilizing part of said conveyer as part of said feeder or distributer, the machine may be economically constructed while having advantages added thereto not otherwise known; and by providing a middlings grader in which the fine middlings are separated from the coarse, and one or both parts reduced or ground, the length of travel of the stock through the machine may be reduced or, in other words, the number of operating steps to which this stock is subjected may be diminished, yet assurance had that all flour which the stock contains will be fully and properly bolted out.

Another advantage of my invention is that middlings may be graded or separated within the roll section of the reel and delivered to separate reduction means so as to more effectively reduce the middlings to flour and to deliver the reduced middlings to suitable means for bolting out the flour under what I term a "short-cut" method; thus saving time while increasing the yield of flour, increasing the capacity of the machine, and consequently reducing the cost of production.

By the use of my improved feeder or distributer in conjunction with reduction means of length, such as provided by the use of a pair of reduction rolls, the stock is spread out and delivered the full length of said rolls in uniform thickness or even flow, thereby assuring increased capacity and greater efficiency in action.

I have found that after passing material through the first pair of break rolls and sifting out the flour from the reduced stock and then passing this stock with the flour removed through reduction rolls and an additional pair of break rolls with intermediate flour-sifting steps, particles of the stock are not fully reduced and a certain percentage of flour is carried out of the machine as part of the offal, and for this reason I have provided means within the reel section for grading the middlings and delivering the coarser portion to a suitable middlings grinder situated outside of the reel

section and then returning the ground material to the reel section for bolting out the flour.

Other advantages of my invention will be clearly apparent from the examination of the drawings and preceding description of the operation of this machine.

Having thus described my invention, what I claim is:—

- 10 1. A mill of the kind described, comprising a casing having a roll section provided with break rolls and reduction rolls, a reel section provided with bolting reels, means for conveying material from said rolls to said reels, means for re-conveying the material from certain of said reels to certain of said rolls including a materials-grader whereby the finer material is delivered to said last-mentioned rolls to be returned to said reel section for further treatment, and independent grinding or reducing means adapted to receive the coarser material from said materials-grader to be returned to said reel section for further treatment.
- 20 2. In a mill of the kind described, the combination of a casing having a roll section equipped with break and reduction rolls, a reel section separated from said roll section and provided with means for bolting the material delivered thereinto, means for conveying material from said rolls to said bolting means, means for re-conveying middlings from said bolting means to certain of said rolls, and means for grading said re-35 conveyed middlings within said roll section preparatory to reducing the same and returning the further reduced material to said bolting means.
- 30 3. In a mill of the kind described, the combination with a casing, of break rolls, reduction rolls, and bolting means within said casing, means for conveying material from said break rolls and reduction rolls to said bolting means, means for re-conveying middlings from said bolting means to said reduction rolls, means for diverting a portion of said middlings, and a separate grinder to receive the diverted portion of said middlings for grinding the same, said grinder being arranged to permit ground material to be returned to said bolting means.
- 40 4. In a mill of the kind described, the combination of break rolls, reduction rolls, bolting means arranged for bolting out flour from flour-producing material, and a separate middlings grinder to receive middlings diverted from said reduction rolls to be returned to said bolting means.
- 50 5. In a mill of the kind described, the combination with a casing having two separate sections, reduction rolls in one of said sections, bolting means in the other section, means for conveying material from said reduction rolls to said bolting means, a separate middlings grinder, means for conveying

separated parts of middlings from said bolting means to said reduction rolls and separate grinder, respectively, and means for bringing the parts of said middlings passed through said reduction rolls and said grinder together to return the same to said bolting means through said conveying means.

6. In a machine of the kind described, the combination of a casing having a roll section provided with break rolls and reduction rolls, a reel section separated from said roll section and provided with a plurality of bolting reels, a shaking device situated above a pair of said break rolls and above a pair of said reduction rolls, said shaking device including a middlings grader, means for conveying material from said break rolls and from said reduction rolls to said bolting reels, means for re-conveying the material from one of said bolting reels to said middlings grader, and a middlings grinder receiving a portion of the middlings from said middlings grader, said middlings grader being adapted to deliver a portion of said middlings to the reduction rolls beneath the same, the reduced middlings passing through said grinder and reduction rolls being conveyed to said reel section for bolting out the flour therefrom.

7. In a mill of the kind described, the combination with a pair of reduction rolls, of a middlings grinder, and a moving middlings grader having a screen portion situated to deliver the finer part of the middlings to said reduction rolls and having means to deliver the coarser part of said middlings to said middlings grinder.

8. In a mill of the kind described, the combination with a casing divided into a roll section and a reel or bolting section, of means for grading middlings in said roll section, different means of reduction receiving the graded middlings, and means for conveying the material having passed through said different means of reduction to said reel or bolting section.

9. In a mill of the kind described, having a roll section, a reel or bolting section in which flour is bolted from stock passed therethrough, means to grade middlings in said reel or bolting sections, a middlings grinder in said roll section, means for conveying one portion of the graded middlings from said reel or bolting section to said middlings grinder, and means to return the ground stock from said middlings grinder to said reel or bolting section.

10. In a mill of the kind described, a reel section having a plurality of bolting reels and means to grade middlings, a middlings grinder situated outside of said reel section, means to convey one part of said graded middlings to said middlings grinder, and means to return the ground middlings having passed through said middlings grinder.

- to another reel within said reel section to bolt out the flour therefrom.
11. A mill of the kind described having a reel section provided with a plurality of bolting reels, one of said bolting reels having fine and coarse silk or wire screens through which flour and middlings, respectively, are passed, a middlings grinder outside of said reel section, means for conveying the middlings from said single mentioned reel to said middlings grinder, and means to convey the ground middlings having passed through said middlings grinder to another bolting reel in said reel section.
12. A mill of the kind described having a reel section provided with a plurality of reels through one of which flour is bolted and from one end of which the coarser material is delivered, an individual middlings grinder, means for conveying said coarser material to said middlings grinder, and means for returning the middlings to any of said reels.
13. A mill of the kind described having a pair of reduction rolls, a middlings grinder comprising a casing and a rotatable grinding element therein, a middlings grader feeding to said reduction rolls and grinder, and means to receive the ground material from said grinder and reduction rolls, said means having connection with said middlings grader to feed middlings thereto.
14. In a mill of the kind described, the combination of a casing having a roll section containing first and second break and first and second reduction rolls, a reel section containing four bolting reels, means for conveying material from said first break rolls to said second break rolls and also to one of said bolting reels, means for conveying finished flour from said reel, means for conveying middlings from said reel to the first reduction rolls, means for conveying material from said first reduction rolls through a second bolting reel, means for conveying flour from said second bolting reel, means for conveying middlings from said second bolting reel to said second reduction rolls, means for conveying tailings from said second bolting reel out of the mill, means for conveying material from said second reduction rolls to a third bolting

reel, means for conveying flour from said third bolting reel, means for conveying tailings out of the mill from said third bolting reel, a scalper receiving material from said second break rolls, means for delivering bran from said scalper out of the mill and for delivering the finer material passing through said scalper into a fourth bolting reel, means for conveying flour from said fourth bolting reel, means for conveying tailings out of the mill from said fourth bolting reel, and means for conveying middlings from said fourth bolting reel to the means for conveying material to said first reduction rolls, the means for conveying material from said first reduction rolls to said second bolting reel, the means for delivering flour from said second bolting reel, the means for conveying material from said second bolting reel to said second reduction rolls, the means for conveying material from said reduction rolls to said third bolting reel, the means for conveying flour from said third bolting reel, and the means for delivering tailings from said third bolting reel being each utilized a second time for run of material not completely disposed of in its first run through the mill.

15. A mill of the kind described comprising a casing having a roll section containing first and second break and first and second reduction rolls, a reel section containing four bolting reels, means for conveying material to said first break rolls, means for dividing the material passed through said first break rolls into two parts, means for conveying one part of said material to one of said bolting reels and the other part thereof to the second break rolls, means for dividing the material passed through said second break rolls into two parts, means for conveying one of said last-mentioned parts out of the mill, means for conveying the other part to a second bolting reel, and means for conveying part of the material passed through said first bolting reel and said second bolting reel through the first reduction rolls and through the remaining bolting reels.

In testimony whereof I affix my signature.

CHARLES T. HOWSON.
